Filed Sept. 17, 1968, Ser. No. 13,569

Term of patent 3½ years

Int. Cl. D21—03

U.S. Cl. D34—5

FIG. 1 is a front elevational view of a roped swing seat or similar article embodying my new design;

FIG. 2 is a cross-sectional view taken on line 2—2 of FIG. 1;

FIG. 3 is a bottom plan view of the structure shown in FIG. 1;

FIG. 4 is a side view of the lower end of the structure shown in FIG. 1;

FIG. 5 is a cross-sectional view taken on line 5—5 of FIG. 2; and

FIG. 6 is a cross-sectional view taken on line 6—6 of FIG. 2.

The broken lines in FIGS. 1 and 4 indicate indeterminate length and the rope is shown fragmentarily in FIGS. 5 and 6 for convenience of illustration.

I claim:

The ornamental design for a roped swing seat or similar article, substantially as shown and described.
